UNITED STATES PATENT OFFICE.

NICHOLAS G. KAISER, OF KANSAS CITY, MISSOURI.

BILLIARD CUE AND METHOD OF MAKING SAME.

Application filed February 21, 1921. Serial No. 446,899.

To all whom it may concern:

Be it known that I, NICHOLAS G. KAISER, a citizen of the United States, residing at Kansas City, in the county of Jackson and 5 State of Missouri, have invented a certain new and useful Improvement in Billiard Cues and Methods of Making Same, of which the following is a specification.

My invention relates to improvements in 10 billiard cues and method of making same.

The object of my invention is to provide a billiard cue which is cheap to make, which is strong and durable and not liable to split or fracture, which will not warp, and with 15 which shots may be easily and accurately made.

A further object of my invention is to provide an improved method of making a cue of the kind described.

20 The novel features of my invention are hereinafter fully described and claimed.

In the accompanying drawing, which illustrates the preferred embodiment of my invention,

25 Fig. 1 is a side elevation of my improved cue.

Fig. 2 is a longitudinal sectional view of the same.

Fig. 3 is a longitudinal sectional view of 30 the sheath.

Fig. 4 is a cross section on the line 4—4 of Fig. 2.

Similar reference characters designate 35 similar parts in the different views.

The cue has a sheath comprising a stem 1 and a handle 2, preferably integral and composed of metal, such as aluminum.

40 Through the stem and handle extends a central longitudinal hole 3 in which is tightly fitted a core 4, preferably of wood, and which extends from the stem and has mounted on its outer end the usual tip 5.

Preferably the core 4 and hole 3 have 45 parallel sides. This permits the core to be cheaply made and to be readily driven into the hole 3.

By having the stem 1 provided with parallel sides, the cue is easily and accurately fingered or guided between the fingers of the hand which is supported on the table. In 50 the ordinary construction commonly used the sides of the cue converge. This requires the guiding finger which embraces the cue to loosely encircle the cue, or to be moved to contract or enlarge the hole through which 55 the cue slides when a shot is being made. Either of these operations tends to reduce the accuracy of cuing. By providing a wooden core and a metal sheath, warping of the cue is prevented as is roughening or 60 splitting of the outer surface.

Suitable weight and balance may be obtained by providing a handle of proper proportions.

Owing to the sides of the stem being parallel, the position of the guiding finger once assumed, need not be changed while a shot is being made.

In order that the core may be securely and permanently retained in the sheath, the 65 latter, before the insertion of the core, may be heated so as to be expanded, and while the sheath is so expanded, the core may be driven in. The subsequent cooling of the sheath will cause it to contract in diameter, so that the core will be very tightly 70 embraced.

I do not limit my invention to the structure shown and described, as modifications within the scope of the appended claim, may 75 be made without departing from the spirit of my invention.

What I claim is:

A billiard cue comprising a handle and a tubular stem, the latter having parallel 85 sides, and a solid core immovably mounted in and extending substantially the length of the handle and stem and projecting from the stem substantially as set forth.

In testimony whereof I have signed my 90 name to this specification.

NICHOLAS G. KAISER.
